LOOSE LEAF BINDER

John Schade, Holyoke, Mass., assignor to National
Blank Book Company, Holyoke, Mass., a cor-
poration of Massachusetts

Application May 11, 1938, Serial No. 207,195

7 Claims. (Cl. 129—17)

This invention relates to an improvement in loose leaf binders particularly for visible index sheets. I disclosed a similar binder in my co-pending application Serial No. 107,028, filed October 22, 1936, now Patent No. 2,141,410, dated December 27, 1938.

The binder now disclosed like my earlier one has two sets of binding posts, one extending from each side into overhanging positions above the binder back. The invention consists in the way these two sets of posts are shifted in their relative positions for useful purposes, particularly for manipulating visible index sheets while holding them in the binder. The subject involves so much detail that it will be described with reference to the accompanying drawings without further introduction.

Fig. 1 shows the posts and binder parts in book closed positions but with the covers laid back and partly cut away;

Fig. 2 is a section on line 2—2 of Fig. 1;

Fig. 3 shows the posts and binder parts in normal position as the bookkeeper would use the book for writing and reference purposes;

Fig. 4 is a view on line 4—4 of Fig. 1;

Fig. 5 shows the posts and binder parts shifted from the position of Fig. 3 into position suitable for one set of posts to be shifted longitudinally of the binder back to take differently spaced positions with the posts in the opposite set, but with the covers removed;

Fig. 6 shows the parts of Fig. 5 in longitudinally shifted positions;

Fig. 7 shows the parts of Fig. 6 again in overlapped positions;

Figs. 8, 9, and 10 are assembly views showing the details of the mechanism for shifting the prongs longitudinally;

Fig. 11 is a detail view of the mechanism for locking the binder in its closed position;

Fig. 12 is a section on line 12—12 of Fig. 1;

Fig. 13 is a section on line 13—13 of Fig. 5;

Figs. 14 and 15 are sections respectively on lines 14—14 and 15—15 of Fig. 11;

Fig. 16 is a detail section on line 16—16 of Fig. 1; and

Fig. 17 is a detail section on line 17—17 of Fig. 1.

The binder shown has a set of arched posts 1, overhanging the back from the right, and another set 2 from the left. These posts are shown by Figs. 1 and 2 in closed book position. They overlap each other the maximum distance transversely of the back and are arranged in widely spaced pairs, the posts of each spaced pair be-

ing, however, spaced the distance between holes in the sheets they are to carry. Thus, posts on each side of the book are spaced from one another, on the same side, a multiple of the distance between a pair of posts 1 and 2. This is one but not the only spacing arrangement, as those familiar with such binders well know.

When the book is opened from the closed position of Fig. 1 to the reading position of Fig. 3, the plan is to carry on a particular mode of operation with reference to the movements of the posts. Starting from the positions of the posts in Fig. 3, it is desirable to shift them relatively through a complete cycle of movements, as follows: first, to the position of Fig. 5 where posts 1 on one side of the binder will not engage holes in the sheets on posts on the opposite side of the binder; second, to the position of Fig. 6 where the posts on the right side have been moved up to give double the spacing between pairs of posts 1 and 2; third, to the position of Fig. 7 where the posts are overlapped as in Fig. 3 but with the spacing between pairs as in Fig. 6; and then just the reverse of the steps referred to so as to complete the cycle back to the position of Fig. 3.

The purpose of the steps in this cycle, as an example, is to help a bookkeeper rearrange his index sheets in the binder without taking the sheets out of the binder. He does this with the sheets wanted for rearrangement exposed on the right-hand side and held by the posts on that side. When the posts are shifted to the position of Fig. 7, the sheets to be changed in position are turned over to rest on the left-hand side of the book. Then the posts on the right-hand side are shifted back to position of Fig. 3 and the sheets are turned over to the right-hand side. In going back to the right-hand side the sheet perforations engaged by the posts on that side will be those spaced one unit below the perforations originally engaged by the same right-hand set of posts. Thus, the visible sheets so handled are all moved up in the book the distance between their perforations or one unit, because they were moved up on the right-hand side, laid on the left-hand posts to hold them up while the right-hand posts were shifted back to their original position in line to take the shifted sheets back one perforation below their former holding positions. It will be obvious that the sheets may be lowered rather than raised in the binder with the help of the same cycle of movement for the posts but a different turning of the sheets. In following through the steps it will be noted that the shifted

sheets were constantly held by one set of posts. At no time was it necessary for the sheets to be taken off the posts and this is a highly desirable condition. Otherwise, a set of index sheets can 5 cause the bookkeeper a lot of trouble in getting out of order. Keeping them on the posts keeps them in order and that is why the book is used.

The present invention consists in the mechanism and mode of operation and convenient arrangement of parts for shifting the posts as 10 stated, and in some detailed binder structure related to the main purpose. The specific structure shown in the drawings can be varied in many ways and the specific illustration is by way of 15 example, except where specifically claimed. This specific example will now be described in detail.

Referring to Fig. 2, the back of the binder has a center line hinge pintle 5. On this are mounted two angular sheet metal hinge leaves 6 and 7 20 with ears like a piano hinge construction. Leaves 6 and 7 are each bent with a horizontal portion having an upstanding and a depending flange. The pintle is at the bottom edges of both 25 depending flanges. Thus, the main frame of the binder back is U-shaped with a depending leaf hinge arrangement along the center line at the bottom.

The hinge leaves 6 and 7 are constantly urged 30 together by a stiff leaf spring 31, of generally circular cross-section, which is snaped into slots in the horizontal surfaces of plates 6 and 7 (see Figs. 1 and 17).

Stiff book covers 3 and 4 are hinged respectively on pintles 10 and 11 at the upper edges 35 of the U-shaped metal back frame made by plates 6 and 7. This is clearly shown in Figs. 1 and 2. The parts 8 and 9, seen in Fig. 2, are merely stiff fiber hood sections riveted to the sides of the U-frame to cover up sheet metal 40 construction and improve the appearance.

Lying within the upstanding flanges of the U-frame formed by plates 6 and 7 are the prong-carrying plates or bars 14 and 16 to which are riveted the prongs 2 and 1 respectively of each 45 prong set. During the longitudinal shifting of the index sheets referred to above, plate 14 remains stationary while plate 16 is shifted back and forth longitudinally of the U-frame by a mechanism to be explained later.

Between the upstanding flanges of plates 6 and 50 7 and the hoods 8 and 9 are mounted anchoring plates 12 and 15 having hook-shaped ears 13 and 13' which pass over the upper edges of the prong-carrying plates 14 and 16 and firmly hold 55 said plates in position against the horizontal and vertical surfaces of plates 7 and 6. As is clear from Figs. 1 and 2, the ears 13 and 13' pass between the hinge eyes on the plates 6 and 7.

Referring now to Figs. 1, 2, 4, and 8, overlying 60 plate 6 is a slide 18, angular in cross-section and with a handle 19 at one end. This slide is mounted to be moved, using the handle 19, from the position of Fig. 3 to that of Fig. 7. The amount of movement of slide 18 between the positions of Figs. 3 and 7 is represented by the length of the slots 20 and 21, which are cut in the horizontal surface of plate 6, see Fig. 8. Slide 18 is held tightly against the horizontal surface of plate 6 by shouldered pins 22 and 23 which are riveted to slide 18 with their shouldered parts 65 underlying plate 6, and which slide in slots 20 and 21. Additional anchorage for slide 18 is provided by a clip 24 spot welded to plate 6, see Figs. 1 and 8.

At that end of slide 18 remote from handle 19

is riveted a cam 25 generally arcuate in cross-section except where it is attached to the surface of slide 18, see Figs. 1, 2, and 4. Cam 25 has an irregular slot composed of two generally slanting sections 28 and 29 and a composite center 5 section, which last is made up of a straight edge 30 on one side of the slot and a peaked section 31 on the opposite side. The cam 25 has a tongue 10 15 20 25 30 35 40 45 50 55 60 65 70 75 80 85 90 95 100 opposite the peaked section for strength, which tongue 32 in the closed position of the book extends through a slot cut in plate 7, see Fig. 2.

Referring now to Figs. 3 and 13, the slot in cam 25 is of the correct width to accommodate a roller 35 pivoted on gooseneck 36, this latter passing through a slot in plate 7 and being riveted to the under surface of said plate. As the slide 18 is moved manually from the position of Fig. 3 to that of Fig. 7 the roller 35 will follow normally the slanting edge 28, the straight edge 30, and then the slanting edge 29 (see Figs. 3 20 and 5 through 7) because of the spring pressure of spring 37 already referred to. Bearing in mind that plates 6 and 7 are pivoted together, it is clear that this motion of the slide will separate the prongs 1 and 2 when the roller 35 is 25 passing along section 28, keep them open as the roller passes along edge 30, and close them again as the roller passes along section 29.

As was explained previously, the prong sets 1 and 2 must be separated sufficiently so that they 30 do not enter the holes in the index sheets carried by each other, before the sheets are shifted longitudinally. Therefore, the slanting sections 28 and 29 are of appropriate dimensions to accomplish this. When, therefore, the roller 35 has 35 reached the position of Fig. 5, the prongs 1 and 2 are ready to be shifted, and it is while the roller 35 is passing along the straight edge 30 from the position of Fig. 5 to that of Fig. 6 that the longitudinal shift of the prong set 1 is made, by 40 mechanism to be explained later. However, it is also true that the only thing necessary is that the prong sets 1 and 2 be kept separated just enough during the longitudinal shifting so that they do not interfere with the index sheets carried by each other. If the prong sets are separated further, the longitudinal shifting will not be 45 affected. This being so, the peaked section 31 of the cam slot allows the operator to spring the plates 6 and 7 further apart during the longitudinal shifting of the prong sets to easily insert new sheets or remove old ones.

The longitudinal shifting of the prong set 1 is done by a rack and gear mechanism shown generally in Figs. 1 and 12, with the details of the 55 operation shown in Figs. 8 through 10. Prong plate 16 has a short angle plate 38 welded to it at a point on its horizontal offset. The angle plate has one arm 39 extending down through a slot cut in plate 6, said depending arm 39 having a 60 set of rack teeth cut along the bottom edge. These rack teeth are engaged by those on a gear 40 pivoted to plate 6, so that the motion of said gear 40 shifts the prong set 1. Gear 40 normally is either in the position shown in Figs. 1 and 8 65 or that shown in Fig. 10, and these positions are controlled by the slide 18. When the slide 18 is in the position shown in Fig. 8, the prong sets are in their separated but non-shifted position of Fig. 5; while when the slide is in the position of Fig. 10, the prongs are in their separated and shifted position corresponding to Fig. 7. The plate 16 is itself guided during the shifting operations by plate 43 riveted to the upper end 70 75 80 85 90 95 100 of plate 6, and overlying the offset portion of plate 6.

plate 16, as well as the ears 13' already referred to.

Gear 40 has a pair of ears 44 and 44' with a notch 45 between them. A portion of gear 40 extends through notches 48 and 49 cut out of the angle made by the horizontal and vertical flanges of plates 6 and 18—see Figs. 4 and 12. A tongue 46 formed integrally with the slide 18 and located at the upper end of slot 49 is of the correct proportion to fit notch 45 in the gear 40, to rotate the gear from the position of Fig. 8 to that of Fig. 10 and thereby shift prongs 1 longitudinally.

The length of slot 49 is such that tongue 46 will not engage the notch 45 as slide 18 is moved, until the prongs are in their separated position shown in Fig. 5. On the other hand the length of slot 48 is merely that necessary to allow gear 40 to turn from one position to the other.

To prevent the prong set 1 from being prematurely shifted, that is before the prongs are in their separated position, I provide locking slots 50 and 50' in the gear 40, see Fig. 8. Slot 50, when the gear is in the position of Fig. 8, is in line with slot 21 in plate 6, and the head of shouldered pin 23 already referred to, lies in this slot 50. As the slide 18 starts to move downward, pin 23 slides along slot 50, thereby preventing the gear 40 from being turned. By the time pin 23 has cleared slot 50, the tongue 46 is sliding along the edge of ear 44' and the gear 40 cannot turn until the tongue 46 reaches notch 45—see Fig. 9.

After the gear 40 is turned to its shifted position of Fig. 10, tongue 46 will slide along the edge 35 of ear 44. By the time tongue 46 has cleared the end of ear 44, slot 50' will be engaged by a locking pin 51 carried, as shown, by slide 18. Plate 6 is provided with an appropriate slot for the pin 51 to slide freely in. Also, referring to 40 Figs. 1 and 12, I have cut away a part 52 of the horizontal surface of plate 7 to accommodate the ear 44 of gear 40 in the closed position of the book.

From the above description it can be seen that 45 there is no possibility of any movement on the part of prongs 1 until the prong sets have been separated by the slide 18 reaching the position of Fig. 5.

Referring to Figs. 1, 11, and 14, the gooseneck member 36 at the beginning of the curve of the gooseneck is provided with a notch 53 in which a locking member 54, associated with plate 6 and having a tongue 55, is bottomed—thereby providing a means to lock the binder in its closed position. Member 54 extends, as shown clearly in Fig. 11, to the bottom of the binder where the end is bent at right angles a short distance beyond the end of plate 6. At this point a Z-shaped plate 56 (see Fig. 15) is welded to the bottom of plate 6 and lies with the shorter leg abutting the depending leg of the plate 6 and under member 54. A flap 57, see Fig. 11, bent out of the plate 56, extends from the short leg to the bottom of plate 6 and parallel to the edge 65 of plate 6 to form with plate 6 a box-like enclosure for a spring pressed plunger 58. Said plunger is in the form of a shouldered pin 60 extending through the flap 57 with the head outside flap 57 and the opposite end riveted to the 70 end of locking member 54. Thus, tongue 55 of member 54 is releasably retained in notch 53. As is shown in Figs. 11 and 14, a web 64 is welded to the bottom of plate 6 to strengthen the binder construction at that point and also support the 75 end of member 54. This web 64 has a short

tongue 65 underlying member 54 with the vertical edge 66 abutting said member 54. This not only provides vertical support for member 54, but likewise keeps it against the depending leg of plate 6.

When the operator wants to open the book from the closed position of Fig. 1 to its normal reading position of Fig. 3, he simply presses the end of member 54 and the roller 35 rises up into the cam slot as the weight of the binder backs is sufficient to overcome the tendency of spring 37 to keep them in the closed position of the book.

As is indicated in Figs. 14 and 11, the curved gooseneck portion of member 35 has a depending flange 67 which starts at the notch 53 and curves towards the opposite edge of member 35. This provides a simple method of camming tongue 55 up so that it will drop into notch 53 when the book is closed.

As will be appreciated from Fig. 13, when the gooseneck member 36 swings up into the cam slot, it must pass through openings in plates 6 and 18. Therefore, I provide suitable notches 68 and 69 cut in the horizontal surface of these parts—see Figs. 8 through 10.

Referring now to Fig. 16, plate 7 is bent downward to form an end closure between the fiber back 8 and the plate itself. While only one end closure is shown it will be understood that the same operation is performed at the other end of this plate. Likewise, plate 6 may be so constructed to form a closure for the back 9 beneath it. Also, I have attached an angle piece 70 to plates 7 and 14 corresponding in height to that 30 of handle 19 of slide 18. The operator can then hold onto piece 70 with one hand while he conveniently operates the slide 18 with the other.

As a further refinement I have shaped the ends of the slot in cam 25 with arcuate portions 72 and 73 conforming to the shape of roller 35, see Fig. 1, so that when the slide 18 is in the position of Fig. 3 or Fig. 7, the roller 35 rests in a definite notch and there is less likelihood of the slide 18 being disturbed while the sheets are being manipulated by the operator.

As is evident from the preceding description, my binder combines many improved construction features of the constituent parts with a simpler mode of operation to achieve a particularly convenient form of binder for this type of work.

What I claim is:

1. In a binder construction for visible index sheets, two sets of oppositely disposed prongs, relatively movable prong supports mounted in 55 the binder to permit one set of prongs to be moved back and forth from an overlapped to a separated position of said prongs as well as to and from two offset positions relatively to the other set of prongs for sheet binding and index 60 shifting purposes in the binder, constraining means cooperating with both of the prong supports to require a change in said overlapped position to take place transversely of the binder far enough to open the prongs for the ends thereof 65 to be free of index sheets before any change can take place in said offset positions and then allow the change in the offset positions to take place while preventing any return to the overlapped position of said prongs where their ends are not 70 free of index sheets during the change in offset positions, but permitting additional separation of said prongs during the change in offset positions, and finally requiring a return of the prongs to the original overlapped position after the 75

change in the offset position is completed, and an actuator operable in one direction to push or in an opposite direction to pull a prong support for coaction against said constraining means, for 5 a sequential operation of first changing the overlapped position, then offset position, and then the overlapped position according to the aforesaid requirement of said constraining means.

2. A binder having centrally pivoted back portions and a set of prongs supported by each back portion, one of such sets being mounted for longitudinal movement between two offset positions relative to the other set and cam mechanism operable to move the relatively pivoted back portions and one set of prongs all in a sequential operation whereby the prongs are spread, offset and overlapped in alternate offset positions upon successive operations of said cam mechanism, said cam mechanism being constructed to allow 10 a separation of the prong sets while said sets are being offset, only after the prong sets have been first separated a definite amount without any change in the offset position.

3. A binder having a back portion including two hingedly connected plates, a set of prongs supported at the side edge of each plate, a slideable bar carrying one set for movement longitudinally of one plate, a rack bar attached to said slideable bar, a pinion on one back plate engaging 15 said rack bar, a slideable cam carrying plate associated with one back plate for operating said pinion, and means connecting the other plate to said cam, whereby upon sliding the cam carrying plate the prong sets are moved back and forth transversely of the binder and one set is moved 20 longitudinally of the other in sequential operation, said cam being constructed to allow, when the plate is reciprocated between its limits, first only a transverse movement of the prong sets, then a composite longitudinal and further transverse movement of the prong sets and finally another transverse movement of said prong sets in the reverse direction.

4. The structure of the foregoing claim 3, having the cam constructed to allow, when the plate is reciprocated between limits, first only a transverse movement of the prong sets and then either a composite longitudinal and transverse movement or only a longitudinal movement of the 25 prong sets and finally another transverse movement of the prong sets in the reverse direction.

5. A binder composed of two back plates each having an upstanding flange at the outside edge and a depending flange at the inner edge, a hinge connecting the lower edges of the depending flanges, a set of prongs supported from each upstanding flange, a slideable plate carrying one of said sets, a device the position of which determines the relative position of the back plates on

their hinge, mechanism which when engaged with said device and said slideable plate is operable to move said device and plate in sequential operation to separate the prongs transversely of the binder, then offset them while allowing additional separation and finally shift them again transversely to their original transverse position whereby the relative position of the prongs in the binder is changed for sheet manipulating purposes, and a releasable locking member which engages the device to keep the book in closed position with the device and mechanism disengaged.

6. A binder having a back portion including two hingedly connected plates, a set of prongs supported at the side edge of each plate, a slideable bar carrying one set for movement longitudinally of one plate, a rack bar attached to said plate, a pinion for engaging said rack bar, a slideable cam-carrying plate associated with one back plate for moving said pinion to shift the prong set longitudinally, the interrelation of the pinion and the cam-carrying plate being such as to make the position of the pinion at all times controlled by the cam-carrying plate, and means connecting the other plate to said cam whereby upon sliding the cam-carrying plate the prong sets are moved back and forth transversely of the binder and one set is moved longitudinally of the other in sequential operation, said cam being constructed to cause a positive transverse movement of the prong sets before and after the cam carrying plate has moved said set longitudinally and to allow additional separation of said sets during said longitudinal movement.

7. A binder having a back portion including two hingedly connected plates, a set of prongs supported at the side edge of each plate, a slideable bar carrying one set for movement longitudinally of one plate, a rack bar attached to said slideable bar, a pinion rotatable to either of two positions to move the slideable prong set longitudinally, said pinion having a pair of ears with locking slots cut in them and a notch between them, an operating slide for said pinion reciprocable between limits and having a fixed lug to slide along the edges of said ears and enter said notch to rotate the pinion from one position to the other as the slide is moved, and a pair of pins carried on said operating slide for engagement with said locking slots, the construction of the pins, lug, and pinion being such that except during rotation of the pinion the pinion is held in position during reciprocation of the slide either by one of the pins being located in its locking slot or by the engagement of said fixed lug along an outer edge of one of said ears.

JOHN SCHADE.
